UNITED STATES PATENT OFFICE

143,754

DESIGN FOR A COLLAR STAY

Peter S. Premas, Chicago, Ill.

Application January 5, 1945, Serial No. 117,275

Term of patent 14 years

(Cl. D17—8)

To all whom it may concern:

Be it known that I, Peter S. Premas, a citizen of the United States, residing at Chicago, in the county of Cook and State of Illinois, have invented a new, original, and ornamental Design for Collar Stays, of which the following is a specification, reference being had to the accompanying drawing, forming part thereof.

Fig. 1 is a top plan view of a collar stay, on an enlarged scale, showing my new design;

Fig. 2 is a side view of the same; and

Fig. 3 is a longitudinal sectional view thereof.

I claim:

The ornamental design for a collar stay, as shown.

PETER S. PREMAS.
